CARBURETOR

Milton E. Chandler, New Britain, Conn., assignor,
by mesne assignments, to Niles-Bement-Pond
Company, West Hartford, Conn., a corporation
of New Jersey

Application July 1, 1943, Serial No. 493,071

9 Claims. (Cl. 261—69)

1

The present invention relates to carburetors, and particularly to carburetors for internal combustion engines, of the type in which the amount of fuel flowing thru the carburetor is proportioned to the quantity of air flowing thru the carburetor.

It is an object of the present invention to provide improved means for controlling the flow of fuel thru a carburetor in accordance with the quantity of air flowing thru it.

Another object of the present invention is to provide an improved carburetor of the type in which the fuel flow is controlled by a main pressure operated valve, and in which the operating pressure for the main valve is controlled by a pilot valve operated in accordance with the flow of air thru the carburetor.

A further object is to provide a carburetor of the type described, in which the fuel, after passing thru the main valve, flows thru a metering restriction, and in which the pilot valve is operated not only in accordance with the air flow thru the carburetor, but in accordance with the fuel pressure on the downstream side of the metering restriction.

Another object of the present invention is to provide an improved pilot valve for a carburetor of the type described.

A further object is to provide improved mechanism for operating a valve in accordance with the resultant of a plurality of variable pressures, in which each of the variable pressures is transmitted to one of a plurality of expandable chambers which are separated by flexible diaphragms. A still further object is to provide, in such a device, improved means for transmitting the forces on the flexible diaphragms to the valve.

Other objects and advantages of my invention will become apparent from a consideration of the appended specification, claims, and drawing, in which

Figure 1 is a somewhat diagrammatic illustration of a carburetor and fuel supply system for an internal combustion engine embodying the principles of my invention.

Figure 2 illustrates a modified form of pilot valve which may be used in the carburetor of Figure 1, and

Figures 3 and 4 illustrate other modified forms of pilot valves which may be used in the carburetor of Figure 1.

Referring now to Figure 1, there is shown a carburetor having a main body 10, through which extends a main air passage 11, between an inlet 12 and an outlet 13. Although any suitable type of

2

carburetor may be used, I prefer to use one of the rectangular type shown and claimed in my co-pending application, Serial No. 406,776, filed August 14, 1941, now Patent No. 2,361,993, issued Nov. 7, 1944.

Air flowing through the passage 11 flows from the inlet 12 past a plurality of parallel Venturi members 14, and past a pair of throttles 15 and a discharge nozzle 16 to the outlet 13. The flow of air through the passage 11 is controlled by the throttles 15, and the flow of air is measured by a Venturi metering arrangement including the Venturi members 14.

A plurality of impact tubes 17 extend into the inlet portion 12 of the passage 11, with their open ends exposed to the flowing air. The impact tubes 17 communicate with a passage 18, commonly termed a vent ring.

Each of the hollow Venturi members 14 is provided with a plurality of lateral openings 20, which openings connect the hollow interiors of the Venturi members 14 with the air passage 11 at or near its narrowest portion. It will be recognized that, in accordance with the known principles of Venturi meters, the difference between the pressure existing at the impact tubes 17 and that existing at the openings 20 in the throat of the venturi, is a measure of the velocity of air flowing through passage 11.

In order to secure proper combustion of the fuel flowing through the carburetor, the mass of fuel flowing per unit time should be proportioned to the mass of air flowing (per unit time), rather than to the velocity of the flowing air. If the air were of constant density, its velocity could be taken as a measure of the mass of air flowing per unit time through passage 11. However, since the density of the air varies with atmospheric pressure and temperature, the pressure differential produced by the Venturi structure must be corrected to obtain a pressure differential which is a true indication of the mass of air flowing through the carburetor.

A portion of the air flowing through the passage 11 enters the impact tubes 17. From there it passes through a second air passage, paralleling a portion of the main air passage 11, and including vent ring 18, a conduit 21, a conduit 22 having a restriction 23 therein, a conduit 24, a valve 25, and a conduit 26 to the interior of the two central hollow Venturi members 14, and out through the openings 20 in those members to the main air passage 11.

A valve 27, located in the valve chamber 25, controls the flow of air through this second pas-

sage. The valve 27 is biased by a spring 31 into engagement with a flexible bellows 28, which is exposed on one side to the pressure in the chamber 25, and on its other side to the pressure in a chamber 32 formed between the bellows 28 and a rigid casing 30. The chamber 32 is filled with nitrogen or other suitable fluid, so that the volume of the chamber 32 varies with the temperature and pressure of the fluid surrounding it. If the density of the flowing air decreases, due either to a decrease in atmospheric pressure such as might be occasioned by an increase in altitude of an aircraft or due to an increase in temperature, the chamber 32 expands, thereby moving the valve member 27 to the right and decreasing the air flow through the second passage previously described. The valve 27 may be so designed and proportioned with respect to restriction 23 in conduit 22, that the pressure differential across the restriction 23 is always an accurate measurement of the mass of air flowing through the main air passage 11, regardless of the variations in the density in the air.

The exterior of the casing 30 is exposed to the air within a chamber 33 formed in the carburetor body 16. In order to maintain the temperature of the air in the chamber 33 at the same temperature as the air passing thru the passage 11, the chamber 33 is connected through a conduit 34 to the interiors of two outer Venturi members 14, which are not used for air flow measurement purposes. Another portion of the chamber 33 is open to the passage 11, as at 35, somewhat downstream from the Venturi members 14. A pressure differential is thereby created which causes a continuous flow of air around the outside of casing 30, thereby insuring that the fluid within the casing is maintained at the same temperature as the air flowing through the carburetor. This condition is further aided by a projection 36 on the casing 30, which extends through the opening 35 a substantial distance into the air passage 11.

The fuel flowing through the carburetor is received from a fuel pump or other source of fuel under superatmospheric pressure (not shown), and passes through a vapor trap 40, a conduit 41, a main fuel regulator valve unit 42, a conduit 43, a mixture control valve 44, a jet system 45, a conduit 46, a pressure regulator valve 47, and a conduit 48 to the discharge nozzle 16.

The vapor trap 40 includes a screen 60, which prevents the passage of foreign materials therethrough. A valve 61 is located at the top of the vapor trap casing and is operated by float 62, so that when the level of the fuel in the vapor trap falls because of the formation of vapor therein, the valve 61 is opened, allowing the vapor to escape through a conduit 63 which may be connected to the fuel tank or to another suitable place for the disposition of the vapor. A ring 64 surrounds a ported sleeve 65, through which the valve 61 moves. The ring 65 is provided so that if the aircraft is flown upside down, it slides down over the ports in the sleeve 65, preventing the drainage of fuel from the vapor trap through the valve 61.

The main fuel regulator valve unit 42 includes a valve member 66 carried by a stem 67, which is attached by any suitable means to the central portion of a flexible diaphragm 68, which is attached at its edges to the casing of the regulator unit 42, so as to divide the casing into a pair of expandable chambers 70 and 51. The valve member 66 cooperates with a seat 71 formed in the

casing of the regulator unit 42. A spring 72, located within the chamber 51 biases the valve member 66 toward open position. The position of valve member 66 is determined by the difference between the pressure in the chamber 70, which acts to close the valve, and the pressure in the chamber 51, aided by the spring 72, both of which act to open the valve. The pressure in the chamber 51 is regulated by the pilot valve unit 54 in a manner more completely described below.

The mixture control valve 44 includes a manually operable shaft 73, carrying a disc valve 74. The disc valve 74 controls the flow of fuel thru a pair of conduits 75 and 76 extending from the mixture control unit 44 to the jet system 45. The disc valve 74 is usually positioned so that either conduit 76 alone is open, both conduits are open, or both are closed. When the conduit 76 alone is open, the carburetor is said to be operating with an "automatic lean" mixture, and when both conduits 75 and 76 are open, the carburetor is said to be operating with an "automatic rich" mixture.

When the conduit 76 is open, fuel flows to the carburetor through a fixed jet 77, and upon the occurrence of a predetermined high pressure differential across the jet system 45, a spring loaded valve 80 opens another jet 78. When the conduit 75 is also opened, a third jet 81 is opened. The maximum flow of fuel through the jets 78 and 81 is restricted by another jet 82. The jet system 45 is quite conventional on carburetors of the type described. It will be understood that the quantity of fuel flowing through the jet system 45 for a given position of the mixture control valve 44, is a function of the pressure differential across the jet system.

The pilot valve unit 54 includes a casing 83 whose interior is divided by three flexible diaphragms 84, 85 and 86 into four expandable chambers 87, 88, 90, and 55. The chamber 87 is connected through a conduit 91 to the conduit 56, and hence the pressure in the chamber 87 is the same as, or at least indicative of, the pressure on the discharge side of the jet system 45. The chamber 88 is connected through a conduit 92 and the conduit 21 to the vent ring 18, so that the pressure in chamber 88 is indicative of the pressure in the inlet 12 of the air passage 11. The chamber 90 is connected through the conduit 93 to the downstream side of the restriction 23 in conduit 22. Therefore, the pressure differential between chambers 88 and 90 is a measure of the mass of air flowing to the carburetor.

A valve member 94 is carried centrally of the diaphragm 86, and cooperates with a seat 95 attached to the casing 83 by any suitable means. The chamber 55 in which the valve member 54 is located, is connected through the conduit 52 with the chamber 51 in the main regulator valve 42. The chamber 53, which receives the fluid discharged through the valve 94, empties into the conduit 58 through a conduit 56 having a restriction 57 therein.

A force transmitting member 96, having a convex upper surface, is attached to the central part of diaphragm 86 by any suitable means. Another force transmitting member 97, having a flat lower surface is attached to the central portion of the diaphragm 85. By reason of the convex surface in the member 96 and the flat surface on the member 97, the two members may engage each other for the transmission of forces from one member to the other, without any lateral binding action between them, regardless

of relative lateral displacement of the diaphragms 85 and 86.

The upper surface of the member 97 is provided with a central recess adapted to receive a projection 98 on the lower surface of a force transmitting member 99 attached to the central portion of diaphragm 87. The force transmitting member 99 is likewise provided with a recess in the central portion of its upper surface, which recess is adapted to receive a guiding projection 100 on a plug 101 which is threadedly mounted in an aperture in the casing 83. The projections 98 and 100, and the recesses with which they cooperate maintain the force transmitting members 97 and 99 in a central position in the casing 83. It will be noticed that the projection 98 is slightly smaller in diameter than the recess in which it moves so as to permit relative lateral movement between the diaphragms 84 and 85.

A tension spring 102 extends between the valve member 94 and a nut 103 threadedly mounted on a bolt 104 extending through the bottom of the casing 83. The bolt 104 is provided with a hexagonal head 105 by which it may be adjusted to vary the tension of the spring 102. A lock nut 106 is provided to fix the bolt 104 so as to maintain any adjustment established for the tension of spring 102.

The pressure in the chamber 87 is maintained at a value greater than atmospheric pressure, by the fuel pump or other similar means. The pressure in chamber 88 is always equal to atmospheric pressure, since that chamber is connected to the vent ring 18. Therefore, the differential pressure acting on the diaphragm 84 tends to move that diaphragm downwardly, and maintains the force transmitting member 99 in engagement with the member 97 attached to diaphragm 85.

In a similar manner, it will be seen that the pressure in chamber 90 is always less than that in chamber 88, since it is established by the suction at the throat of the venturi. The force acting on diaphragm 85 is, therefore, downward.

The pressure in the chamber 55 is larger than the pressures in any of the other three chambers, since it is connected to the upstream side of jet system 45 through the conduit 52 and restriction 50. Therefore, the pressure below the diaphragm 86 is higher than the pressure above it, and the force acting on diaphragm 86 is upward, tending to maintain the member 96 in engagement with member 97.

The force acting on diaphragm 86, therefore, tends to open the valve 94, while the forces acting on diaphragms 84 and 85 tend to close the valve 94. These latter two forces are aided by the tension of spring 102. As the valve 94 moves towards its open position, the pressure in chamber 55 is released, thereby decreasing the force tending to move the valve toward open position. Likewise as the valve 94 moves towards its closed position the pressure in chamber 55 is increased thereby building up an opposing force tending to stop the motion of the valve. It may, therefore, be seen that the valve 94 is positioned so as to regulate the pressure in the chamber 55 in accordance with the resultant of the pressures in the chambers 87, 88, and 90.

As previously described, the differential between the pressures in the chambers 88 and 90 of the pilot valve unit 54 is a measure of the mass of air flowing per unit time thru the passage 11. This pressure differential produces a force acting downwardly on diaphragm 85 which is likewise a measure of the mass of air flowing per unit time.

The pressure in chamber 55 is indicative of the pressure in the fuel line on the upstream side of the jet system. The pressure in chamber 87 is indicative of the pressure in the fuel line on the downstream side of the jet system. The differential between these two fuel pressures provides a force acting upwardly on the valve 94. The air pressure differential acting on diaphragm 85 acts in a direction to close valve 94 and the fuel pressure differential acts to open valve 94. Closure of valve 94 results in an increase in pressure in chamber 55 which is transmitted thru conduit 52 to chamber 51 and acts on diaphragm 68 to move valve 66 in an opening direction. It may, therefore, be stated that the air pressure differential acts on the pilot valve 94 in a fuel flow increasing direction, the fuel flow referred to being the flow thru the main fuel line. Conversely, the fuel pressure differential acts on the pilot valve 94 in a fuel flow decreasing direction. The pilot valve unit balances the air pressure differential against the fuel pressure differential and corrects the fuel flow to regain a condition of balance in case the two pressure differentials become unbalanced.

A pilot valve unit 54 is formed from an upper casting 89 and a lower casting 83. In assembling this unit, the diaphragm 86 has its edges attached to casting 83 by the bolts between upper and lower plates as shown in the drawing, so that the chamber 55 is formed under the diaphragm 86 between the diaphragm and the lower plate. In a similar manner the diaphragm 84 is clamped to the upper casting 89, forming with the central recess in that casting the chamber 87. The two castings are then placed together, clamping the edges of the diaphragm 85 between them and are then fastened in that position. This completes the structure of the four chambers of the pilot valve unit. It should be noted that the diaphragms carry the force-transmitting members 96, 97 and 99 at their centers, so that the mechanism for transmitting the forces to the valve is completed by the act of assembling the diaphragms and the two castings of the housing.

The regulator valve 47 is attached to a diaphragm 110, which is exposed on one side to the inlet pressure of the fuel flowing thru the valve 47 and on its opposite side to the pressure in a chamber 111 connected through a conduit 112 to the vent ring 18. A spring 113 aids the pressure in the chamber 111 in balancing the force due to the pressure on the opposite side of diaphragm 110. The function of the regulator valve 47 is to maintain a substantially constant pressure inside the discharge nozzle 16, so that the fuel flow through the discharge nozzle will not be affected by variations in the pressure in the air passage 11 downstream from the throttles 15.

An idling valve 114 is located in the conduit 46 between the jet system 45 and the regulator valve 47. The idling valve 114 is connected by a linkage, (not shown), to the throttles 15, so that when the throttles are moved toward their closed positions the idling valve 114 is moved towards its closed position to decrease the fuel flow therethrough. In a carburetor of the type described, the differential pressure in the chambers 88 and 90 is so small at low air flows that it exerts no appreciable controlling effect on the fuel flow.

The spring 102 acts on the valve 94 in a closing direction. As previously pointed out, movement of valve 94 towards closed position tends to cause an opening movement of valve 66 and a consequent increase in fuel flow. The spring 72 directly biases the valve 66 in a fuel flow increasing

direction. At the higher rates of air and fuel flow, the forces of these two springs are small as compared to the forces of the air and fuel pressure differentials. At low air flows, however, these two springs predominate over the air and fuel pressure differentials and therefore tend to produce a greater fuel flow than necessary. At such times, the idle valve 114, which is linked to the throttle, moves into a position wherein it restricts the fuel flow. The fuel flow in the idle range is therefore controlled from the throttle position and not by the air flow. The effect of the springs 72 and 102 is to transfer control of the fuel flow from the air flow measuring system to the throttle in the idle range.

Figure 2

There is shown in Figure 2 a modified form of the pilot valve unit which may be used in place of the pilot valve unit 54 in Figure 1. In Figure 2, the conduits 52, 56, 91, 92 and 93 correspond to the conduits having the same reference characters in Figure 1. In Figure 2, there is shown a casing 120 whose interior is divided by three flexible diaphragms 121, 122, and 123 into four expandable chambers 124, 125, 126 and 127. These chambers respectively correspond to the chambers 87, 88, 90 and 55 of Figure 1. In the device of Figure 2, the diaphragms 121 and 122 are rigidly connected by a valve operating member 128, which extends to the right beyond the diaphragm 122, and is provided with a flange 130 at its right hand end. The central portion of diaphragm 123 is clamped between a pair of discs 131 and is adapted to cover a port 132 in the casing 120, thereby controlling the flow of fluid between the chamber 127 and conduit 56, and hence the pressure in the chamber 127.

As in the case of the pilot valve in Figure 1, the pressure acting on the diaphragms 121 and 122 tends to move the member 128 in a valve-closing direction while the pressure acting on diaphragm 123 tends to move it and the discs 131 in a valve opening direction. The opposition of these pressures maintains the left hand disc 131 in engagement with the flange 130 on the member 128.

It is believed that the operation of the device shown in Figure 2 will be clear from the description of the operation of the pilot valve unit 54 of Figure 1.

Figure 3

The pilot valve shown in Figure 3 may also be used in place of the pilot valve structure of Figure 1. In Figure 3 there is shown a casing 140 divided by three flexible diaphragms 141, 142, and 143 into four expandable chambers 144, 145, 146, and 147, which correspond respectively to the chambers 87, 88, 90 and 55 of Figure 1. A sleeve 150 extends through the central portion of all of the diaphragms 141, 142 and 143. The diaphragms are clamped to the sleeve 150 by means of a series of rings 151, 152 and 153. These rings surround the sleeve 150, and one of the diaphragms is clamped between each adjacent pair of rings, with the exception of diaphragm 143, which is clamped between ring 153 and a flange 154 on the lower end of sleeve 150. The upper ring 151 is threaded on the sleeve 150, so as to maintain all the rings, the diaphragms, and the sleeve in assembled relation.

A post 156 extends through the sleeve 150, and has a tapered portion 157 which cooperates with the edge of an interior flange 158 on the sleeve 150 to form a valve and seat arrangement. The

post 156 has an extension 160, of relatively small diameter, which extends through the port formed by the opening in the flange 158. The extension 160 carries a stop member 161 which limits the upward movement of the sleeve 150. The post 156 is provided with laterally projecting surfaces such as that shown at 162, which guide the movement of the sleeve 150 and prevent it from tilting.

In the construction shown in Figure 3, the valve mechanism controls the flow of fluid between the chambers 147 and 144. It is, therefore, unnecessary to provide an additional outlet chamber for conveying the fluid discharged through the valve to the conduit 58, such as the chamber 53 and conduit 56 of Figure 1. The construction is thereby simplified. The operation of the device is otherwise the same as that of the device shown in Figure 1 and it is believed that further explanation of it is unnecessary.

Figure 4

There is shown in Figure 4 still another modified form of pilot valve which may be used in place of the valve unit 54 of Figure 1. In the arrangement of Figure 4, a casing 170 is divided by a diaphragm 171 into two expandable chambers 172 and 173, which functionally correspond to the chambers 88 and 90 of Figure 1. Within the chamber 173 is mounted a cylindrical member 174, having a partition 175 extending across it. An aperture 176 extends through the partition 175. A diaphragm 177 is clamped between the lower edge of cylinder 174 and the casing 170, and separates the space between the partition 175 and the bottom of casing 170 into two expandable chambers 178 and 180. Another diaphragm 181 is clamped to the upper surface of the cylindrical member 174 by means of a ring 182. Another expandable chamber 183 is thereby formed between the diaphragm 181 and the partition 175.

The chamber 183 corresponds functionally to the chamber 55 of Figure 1, while the chamber 178 corresponds to the chamber 87 of Figure 1. The chamber 180 has no counterpart in Figure 1, but is provided merely to balance the force produced by the pressure in chamber 173 on the upper side of diaphragm 181. For this purpose, chamber 180 is connected thru a conduit 193 to conduit 93, so that the pressure is the same in both chambers 173 and 180.

The diaphragms 181 and 177 are rigidly attached by a rod 184, and the diaphragm 181 carries, adjacent the aperture 176 in partition 175, a valve member 195 which cooperates with that aperture to close and open it.

The upper end of rod 184 is provided with a convex head which cooperates with a flat surface on the lower side of a force transmitting member 186 carried by the diaphragm 171. The member 186 is provided with a recess in its upper surface, which cooperates with a guide rod 187, attached to the casing 170.

Another guide member 190 cooperates with the outer surface of member 186. The guide member 190 comprises an outer annular portion attached to the casing 170 by any suitable means such as bolts 191, and an inner conical portion which is centrally apertured to permit passage of the member 186.

A compression spring 188 is retained between the member 186 and the casing 170, and biases the valve 185 toward closed position.

While I have shown and described certain preferred embodiments of my invention, other modifications thereof will occur to those skilled in the

art and I therefore intend that my invention shall be limited only by the appended claims.

I claim as my invention:

1. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit including a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member having a port therein, a valve member movable with respect to said seat member to open and close said port, a housing, at least three flexible partitions extending transversely of said housing to provide four expansible chambers in said housing, sleeve means attached to all said partitions and carrying one of said members so that said one member is positioned in accordance with the resultant of the forces acting on said partitions, means for supplying to two of said chambers fluid under said two unequal pressures so that an increase in the difference between said two pressures tends to cause a closing movement of said valve member, means connecting a third of said chambers to said second conduit at the discharge side of said restriction, means connecting the fourth of said chambers to said third conduit so that the difference between the pressures in said third and fourth chambers tends to cause an opening movement of said valve member, and a passage thru said sleeve means connecting said third and fourth chambers and controlled by said valve and seat members, said passage, said third and fourth chambers and their associated connecting means forming a portion of said third conduit.

2. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit includ-

ing a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member, a valve member movable with respect to said seat member, a housing for said members, at least three flexible partitions extending transversely of said housing to provide four expansible chambers in said housing, means for transmitting the forces acting on said flexible partitions to at least one of said members to control the relative positions of said members, means for supplying to two of said four chambers fluid under said two unequal pressures so that an increase in the difference between said two pressures tends to cause a closing movement of said valve member, means connecting a third of said four chambers to said pressure regulating means, and means connecting the fourth of said four chambers to said third conduit so that the difference between the pressures in said third and fourth chambers tends to cause an opening movement of said valve member, said third and fourth chambers being adjacent each other and interconnected by said valve and seat members, and forming therewith a portion of said third conduit.

3. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit including a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member, a valve member movable with respect to said seat member, a housing for said members, at least three flexible partitions extending transversely of said housing to provide four expansible chambers in said housing, means for transmitting the forces acting on said flexible partitions to at least one of said members to control the relative positions of said members, means for supplying to two of said four chambers fluid under said two pressures so that an increase in the difference between said two pressures tends to cause a closing movement of said valve member, means connecting a third of said four chambers to said pressure regulating means, and means connecting the fourth of said four chambers to said third conduit so that an increase in the difference between the pressures in said third and fourth chambers tends to cause an opening movement of said valve member, said members

controlling a passage interconnecting said third and fourth chambers, and forming with said third and fourth chambers a portion of said third conduit.

4. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit including a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member, a valve member movable with respect to said seat member, a housing, at least three flexible partitions extending transversely of said housing to provide four expansible chambers in said housing, means for transmitting the forces acting on said flexible partitions to at least one of said members to control the relative positions of said members, stop means for limiting the opening movement of said valve member with respect to said seat member, means for supplying to two of said four chambers fluid under said two unequal pressures so that an increase in the difference between said two pressures tends to cause a closing movement of said valve member, means connecting a third of said four chambers to said pressure regulating means, and means connecting the fourth of said four chambers to said third conduit so that an increase in the difference between the pressures in said third and fourth chambers tends to cause an opening movement of said valve member, said members controlling a passage interconnecting said third and fourth chambers, and forming with said third and fourth chambers a portion of said third conduit.

5. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit including a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member having a port therein, a valve member movable with respect to said seat member to open and close said port, a housing, at least three flexible partitions extending transversely of said housing to provide four expansible chambers in said housing, means for transmitting the forces acting on said flexible partitions to at least one of said members to control the relative positions of said members, means for supplying to two of said four chambers fluid under said two unequal air pressures so that an increase in the difference between said two pressures tends to cause a closing movement of said valve member, means connecting a third of said four chambers to said pressure regulating means, and means connecting the fourth of said four chambers to

ing a movable wall attached to said first valve means for positioning the same, and second valve means for controlling the flow of fluid thru said third conduit and thereby the pressure in said chamber and the position of said first valve means, said second valve means comprising a housing, at least three flexible partitions extending transversely of said housing to provide four expansible chambers therein, sleeve means attached to all said partitions and having a passage therethru interconnecting the chambers at the opposite ends of said housing, a valve member carried by said sleeve means at one end thereof, a seat member attached to said housing for cooperation with said valve member to control the flow of fluid thru said passage, mounting means for said seat member comprising a post extending thru said passage for guiding the movements of said sleeve means, means for supplying to two of said chambers fluid under said two unequal pressures so that an increase in the difference between said two pressures tends to cause a closing movement of said valve member, means connecting a third of said chambers to said second conduit at the discharge side of said restriction, and means connecting the fourth of said chambers to said third conduit so that the difference between the pressures in said third and fourth chambers tends to cause an opening movement of said valve member, said passage connecting said third and fourth chambers and forming therewith a portion of said third conduit.

6. A carburetor for an internal combustion engine, comprising in combination, a first conduit for conveying air for combustion purposes to said engine, metering means in said first conduit for producing two unequal pressures therein whose difference is a measure of the quantity of air flowing therethru, a source of fluid fuel under superatmospheric pressure, a second conduit for conveying fuel from said source to said engine, a metering restriction in said second conduit, means for regulating the fuel pressure in said second conduit at the discharge side of said restriction, first valve means for controlling the fuel pressure on the intake side of said restriction and thereby controlling the flow of fuel therethru, means for operating said first valve means including a third conduit for by-passing fuel from said source around said restriction to said fuel pressure regulating means, said third conduit including a restriction, an expansible chamber having a movable wall attached to said first valve means for positioning the same, and second valve means for controlling the flow of fluid thru said third conduit and thereby the pressure in said chamber and the position of said first valve means, said second valve means comprising a seat member having a port therein, a valve member movable with respect to said seat member to open and close said port, a housing, at least three flexible partitions extending transversely of said housing to provide four expansible chambers in said housing, means for transmitting the forces acting on said flexible partitions to at least one of said members to control the relative positions of said members, means for supplying to two of said four chambers fluid under said two unequal air pressures so that an increase in the difference between said two pressures tends to cause a closing movement of said valve member, means connecting a third of said four chambers to said pressure regulating means, and means connecting the fourth of said four chambers to

said third conduit so that an increase in the difference between the pressures in said third and fourth chambers tends to cause an opening movement of said valve member.

7. Fuel and air proportioning apparatus for an internal combustion engine, comprising a conduit for combustion air flowing to said engine, means associated with said conduit for producing two unequal pressures whose difference is a measure of the rate of flow of air thru said conduit, a conduit for fuel flowing to said engine, a metering restriction in said fuel conduit for regulating the flow of fuel therethru in accordance with the fuel pressure differential established thereacross, means for maintaining a substantially constant pressure in said fuel conduit on the downstream side of said restriction, and means for controlling the pressure on the upstream side of said restriction including a valve, an expandible chamber having a movable wall subject on its external surface to the pressure controlled by said valve, a restricted inlet passage for admitting fuel to said chamber from the fuel conduit on the upstream side of said restriction, a restricted outlet passage for discharging fuel from said chamber to said fuel conduit at the downstream side of said restriction, and pilot valve means responsive to the difference of said two unequal air pressures for varying the cross-sectional area of one of said restricted passages.

8. Apparatus for positioning a valve to be operated in accordance with the resultant of four variable pressures, comprising a generally cylindrical housing, three parallel flexible diaphragms extending transversely of said housing and separating said housing into four expandible chambers, three separately movable, rigid force-transmitting members, one mounted substantially centrally of each of said diaphragms, first guide means including cooperating guide elements on one end of said housing and on the force-transmitting member on the diaphragm nearest said one end, second guide means including cooperating guide elements on the other end of said housing and on the force-transmitting member on the diaphragm nearest said other end, third guide means including cooperating guide elements on the force-transmitting member of the center one of said diaphragms and on the force-transmitting member of one of the adjacent diaphragms, cooperating surfaces on the force-transmitting member on said center diaphragm and on the force-transmitting member on the other adjacent diaphragm, one of said surfaces being rounded and the other flat to permit relative lateral movements of said center diaphragm and said other adjacent diaphragm and to transmit only forces acting normal to the point of contact of said surfaces, means directly connecting one of said diaphragms to said valve, and means for supplying each of said four chambers with a fluid under one of said four variable pressures, so as to apply to each of the diaphragms not directly connected to the valve a force acting toward said directly connected diaphragm and thereby to hold

said members in engagement with one another and to operate said valve in accordance with the resultant of said pressures.

9. Apparatus for positioning a valve to be operated in accordance with the resultant of four variable pressures, comprising a pair of complementary housing members, each housing member having a first generally cylindrical recess in one face thereof and a second generally cylindrical recess of smaller diameter at the bottom of said first recess, a valve seat in one of said second recesses, three diaphragm units, each unit comprising a flexible diaphragm and a rigid force-transmitting member mounted substantially at the center thereof, means for clamping the periphery of the diaphragms of two of said units to the edges of said second recesses in said two housing members so that said two units with their associated recesses form expandible chambers, a valve carried by the one of said two units adjacent said valve seat for cooperation with said seat, the third of said units being adapted to have its periphery clamped between the edges of said first recesses when said housing members are fastened together, so that said third unit forms with said first recesses two more expandible chambers, each pair of adjacent force-transmitting members having cooperating surfaces which permit relative lateral movements of said members, said units including all the force-transmitting mechanism between said diaphragms, so that said members are assembled in force-transmitting relation by the assembling of said units and said housing members, means for supplying to each said chamber a fluid under one of said variable pressures, so that, for each of said units except the one carrying said valve, the pressure on the side farthest from said valve is greater than the pressure on the side nearest said valve, each said force-transmitting member being moved toward said valve by the pressure differential acting on its associated diaphragm, so that said force-transmitting members are stressed in compression and said cooperating surfaces are maintained in contact to position said valve in accordance with the resultant of the pressures in all said chambers.

MILTON E. CHANDLER.
